UNITED STATES PATENT OFFICE.

DUDLEY S. SEYMOUR, OF OAK PARK, ILLINOIS, ASSIGNOR TO UNION SPECIAL MACHINE COMPANY, OF CHICAGO, ILLINOIS, A CORPORATION OF ILLINOIS

FILLED-BAG-SEWING APPARATUS.

1,248,731.

Specification of Letters Patent.

Patented Dec. 4, 1917.

Application filed May 9, 1912, Serial No. 696,165. Renewed April 25, 1917. Serial No. 164,525.

To all whom it may concern:

Be it known that I, DUDLEY S. SEYMOUR, a citizen of the United States, residing at Oak Park, in the county of Cook, State of Illinois, have invented certain new and useful Improvements in Filled - Bag - Sewing Apparatus, of which the following is a description, reference being had to the accompanying drawing and to the figures of reference marked thereon.

The invention relates to new and useful improvements in devices for sewing filled sacks, and more especially to devices of this character where the sack is brought by a conveyor to the stitching mechanism, and also simultaneously fed past the stitching mechanism with the feed of the sewing machine.

In devices of this character, it is essential to provide means whereby the conveyor may be driven independently of the stitching mechanism, so that the filled bag may be placed on the conveyor and the conveyor started so as to bring the sack to a point adjacent the stitching mechanism, before the stitching mechanism is set into operation.

In this type of machine, the operator is required to use both hands in properly placing the mouth of the sack so that it may be fed to the stitching mechanism, and therefore, it is also essential to provide a controlling device which may be operated by the foot or knee of the operator so that the conveyor and the stitching mechanism may be started and stopped whenever desired.

An object of the present invention is to provide a controlling member for the driving devices of the conveyor and sewing mechanism, which controlling member may be operated so as to control the conveyor and the stitching mechanism in succession by a single movement of the controlling lever.

A further object of the invention, is to provide two independent driving connections for the sewing mechanism and conveyor respectively, which driving connections include separate transmitters and a common controlling mechanism for the two transmitters, which is so constructed that one transmitter may be operated in advance of the other.

These and other objects will in part be obvious, and will in part be hereinafter more fully described.

55 In the drawings which show by way of

illustration one embodiment of the invention;

Figure 1 is an end view of a filled sack sewing machine, having my improvements applied thereto, many of the parts being shown more or less diagrammatically;

Fig. 2 is a rear view of the same.

In carrying out the invention, I have provided a filled sack sewing machine with a driving motor which has independent driving connections with two separate transmitters. One of the transmitters is connected to the sewing mechanism and the other transmitter is suitably connected to the conveyor so that the conveyor and sewing mechanism may be independently controlled and thereby the conveyor caused to bring the filled sack to the stitching mechanism, prior to the operation of the stitching mechanism.

The invention consists further in a single lever which is connected with one of the transmitters through a yielding device which permits the controlling lever to move relative to the transmitter after the transmitter is closed, for imparting or transmitting a driving motion to the conveyor, and a separate connection between said controlling lever and the other transmitter, which connection includes a certain amount of lost motion whereby the controlling lever may be moved through a limited distance before closing the transmitter.

Referring more in detail to the drawings, the invention consists of a filled bag sewing machine having a supporting frame 1 which is provided with suitable brackets on which is mounted a traveling conveyor 2. This conveyor is operated by a cross shaft 3, which carries a gear meshing with a worm 4 on a vertical shaft 5. This vertical shaft 5, at its lower end, is provided with a belt wheel 6. Mounted in suitable brackets adjacent the belt wheel 6, are suitable belt wheels 7 and 8. These belt wheels are mounted to turn about an axis at right angles to the axis of the belt wheel 6, and merely serve as guiding wheels to change the direction of movement of a belt 9 which cooperates with the belt wheel 6 and also operates with a driven belt wheel carried by the transmitter 10. This transmitter is similar in construction to that shown and described in my prior Patent No. 854,671, granted May 21, 1907. It will not be necessary to describe the transmitter in detail,

but merely to point out that said transmitter includes a driven belt wheel 11 with which the belt 9 coöperates, and a second belt wheel 12, which coöperates with a belt 13 which in turn engages a belt wheel 14 on the shaft of a suitable motor 15. Said driven wheel of the transmitter is normally held disconnected from the driving wheel of the transmitter by a suitable spring, and said transmitter is closed, that is, the friction surfaces interposed between the driving and driven members, are brought into contact by a swinging lever 16.

Mounted near the upper part of the frame 1, is a sewing machine 17 which consists of the usual bed plate 18, overhanging arm 19, which carries a needle head in which vibrates a needle 20. Coöperating with the needle is the usual complementary stitch forming mechanism and the usual feed of the sewing machine. The parts are operated from a driving wheel 21. These parts are of such common use that further description of the stitching mechanism is not thought necessary. The driving wheel of the sewing machine is operated by a belt 22 which engages a driven wheel 23 on a transmitter 24. Said belt runs over suitable guide wheels 25, 25. This transmitter 24 is similar in construction to the transmitter 10 and the transmitter is closed by a lever 26. The transmitter 24 is driven by a belt 24^a which coöperates with a belt wheel 24^b on the shaft of the motor 15.

35 The two transmitters are controlled by a lever or rock shaft 27 which is provided with an arm 28 and a foot treadle 29, both of which are rigidly attached to the shaft 27. A rod 30 is connected at its lower end 40 to an eye 31 formed in the outer end of the arm 28. The upper end of the rod is connected with the lower end of a coiled spring 32. The upper end of the coiled spring is connected at 33, with the lever 16 which controls the transmitter 10. The rod 30 as herein shown is made in two parts which are clamped together by suitable collars 34 and 35. The purpose of these collars is to permit the length of the rod 30 to be adjusted, so that the position of the treadle 29 relative to the floor may be shifted. A rod 36 is connected at its upper end at 37, with the lever 26. Said rod at its lower end is connected at 38 with a collar 39 which 55 slides freely on the rod 30. A fixed collar 40 is clamped to the rod 30 at a point above the normal position of the collar 39.

The operation of my device is as follows: The motor 15 continuously operates the 60 driving pulleys of the two transmitters 10 and 24. The filled sack is placed on the conveyer. The treadle 29 is depressed sufficiently to close the transmitter 10. Inasmuch as the collar 40 is spaced above the 65 collar 39, the movement of the treadle which

shifts the rod 30 sufficiently to close the transmitter 10, will not operate the transmitter 24, but will merely bring the collar 40 into contact with the upper face of the collar 39. This closing of the transmitter 70 10 therefore, causes the conveyer to travel and bring the filled sack to the stitching point, but the stitching mechanism is not yet placed in action. A further depression of the treadle 29, will cause the lever 26 to 75 close the transmitter 24 as the collar 40 is now in contact with the collar 39, and a further downward movement of the treadle will pull down the rod 36 and close the transmitter.

The coiled spring 32 will yield to allow a further movement of the rod 30 after the transmitter 10 is closed, so that the lever 16 cannot be further moved. Upon releasing the treadle slightly, the rod 30 will move upwardly through the action of the spring 32, and the spring controlling the transmitter lever 26 will cause the transmitter 24 to open or release the driven wheel, and the stitching mechanism to stop. A further upward movement of the treadle will release the transmitter 10, and cause the conveyer to stop.

From the above description, it will be apparent that I have provided driving connections for the conveyer and stitching mechanism which may be successively controlled from a single lever so that the conveyer may be first operated and subsequently the stitching mechanism thrown 100 into action.

While I have shown two independent transmitters, it will be obvious that from certain aspects of the invention, the controlling lever and the devices intermediate the controlling lever and the transmitters, may be used with other forms of clutch devices than the transmitters, the essential feature being the single lever with the intermediate mechanism whereby the conveyer may be 110 driven independently of the stitching mechanism.

It is obvious that minor changes in the details of construction and arrangement of parts may be made, without departing from 115 the spirit of the invention, as set forth in appended claims.

Having thus particularly described my invention, what I claim as new and desire to secure by Letters Patent is:

1. In an apparatus for sewing filled sacks, the combination with sewing mechanism, a conveyer, independent driven devices for operating said sewing mechanism and said conveyer, a controlling member, and devices 125 intermediate said controlling member and said driving devices, whereby said driving devices may be each manually set into operation in succession.

2. In an apparatus for sewing filled sacks,

the combination of a sewing mechanism, a conveyer, independent driving members, a motor for operating said independent driving members, a controlling treadle, and devices intermediate of said driving members and said treadle, whereby said driving members may be set into operation in succession.

3. In an apparatus for sewing filled sacks, 10 the combination of sewing mechanism, a conveyer, a driven member for operating the sewing mechanism, a driven member for operating the conveyer, a lever, controlling devices intermediate said lever and said driven members, said controlling devices being so constructed that one of the driven members may be operated independently of the other.

4. In an apparatus for sewing filled sacks, 20 the combination of sewing mechanism, a conveyer, a motor, a transmitter intermediate said motor and said sewing mechanism, a transmitter intermediate said motor and said conveyer, a controlling lever, and means intermediate the controlling lever and the transmitters, whereby one transmitter may be operated from the lever independently of the other.

5. In an apparatus for sewing filled sacks, 30 the combination of sewing mechanism, a conveyer, a motor, a transmitter intermediate said motor and said sewing mechanism, a transmitter intermediate said motor and said conveyer, a controlling lever, means intermediate the lever and the transmitters including devices whereby first one transmitter and then the other may be operated by a movement of the lever in the same direction.

40 6. In an apparatus for sewing filled sacks, the combination of sewing mechanism, a conveyer, a motor, a transmitter intermediate said motor and said sewing mechanism, a transmitter intermediate said motor and said conveyer, a controlling lever, a rod connection intermediate said lever and one of the transmitters, said rod connection including a spring, a rod connection between said lever and the other transmitter, said rod connection including devices having a lost motion, whereby the treadle may be shifted to a certain extent before operating said last-named transmitter.

7. In an apparatus for sewing filled sacks, 55 the combination of sewing mechanism, a conveyer, a motor, a transmitter intermediate said motor and said sewing mechanism, a transmitter intermediate said motor and said conveyer, an arm, a rod connected to said arm, a spring connected to the rod and to one of the transmitters, a collar fixed to the rod, a second rod connected to the other transmitter and to a collar loose on the first rod, and disposed below said fixed collar, 60 and means for swinging said arm.

8. In an apparatus for sewing filled sacks, the combination of sewing mechanism, a conveyer, a motor, a transmitter intermediate said motor and said sewing mechanism, a transmitter intermediate said motor and said conveyer, an arm, a rod connected to said arm, a spring connected to the rod and to one of the transmitters, a collar fixed to the rod, a second rod connected to the other transmitter and to a collar loose on the first rod, and disposed below said fixed collar, a rock shaft supporting the arm, and a treadle fixed to the rock shaft for swinging said arm.

9. In an apparatus for sewing filled sacks, 80 the combination of a sewing mechanism, a conveyer, a motor, a transmitter intermediate said motor and said sewing mechanism, a transmitter intermediate said motor and said conveyer, an arm, a rod connected to said arm, a spring connected to the rod and to one of the transmitters, a collar fixed to the rod, a second rod connected to the other transmitter and to a collar loose on the first rod, and disposed below said fixed collar, a rock shaft supporting the arm, and a treadle fixed to the rock shaft for swinging said arm, said rod connection between the arm and the first transmitter being adjustable whereby the position of the treadle 90 may be shifted.

10. In a filled bag sewing machine, a sewing mechanism and a conveyer, a controlling member, means interposed between the sewing mechanism and conveyer and the controlling member, whereby the initial movement of the controlling member operates the conveyer, and a further movement of the controlling member operates the sewing mechanism and conveyer together.

11. In a filled bag sewing machine, a sewing mechanism and a conveyer, a controlling member, means interposed between the sewing mechanism and conveyer, whereby the initial movement of the controlling member operates the conveyer, and a further movement of the controlling member operates the sewing mechanism, and automatic means to first stop the sewing mechanism and then the conveyer.

12. In a filled bag sewing machine, a sewing mechanism and a conveyer, a belt-operated member for transmitting power to the conveyer, a second belt-operated member for transmitting power to the sewing mechanism, and a controlling member for separately or conjunctively operating the belt-driven members.

13. In a filled bag sewing machine, a sewing mechanism and a conveying mechanism, 125 separate driving members for operating said sewing mechanism and said conveying mechanism, said driving mechanisms being operated from the same source of power, and a controlling device and separate de-

1. vices operated by said controlling device for independently regulating the operation of said sewing mechanism and conveyer.

14. A filled bag sewing machine comprising a sewing mechanism, a conveyer, a driving member for said sewing mechanism, idlers interposed between said driving member and the sewing mechanism, a belt passing over said idlers for operating the sewing mechanism from said driving member, a driving member for said conveyer, idlers, a belt passing over said last named idlers

for operating the conveyer from said last named driving member, means for operating said driving members, and manually operated means for independently controlling the action of said driving members. 15

In testimony whereof, I affix my signature in the presence of two witnesses.

DUDLEY S. SEYMOUR.
